UNITED STATES PATENT OFFICE.

JACOB STEIN, OF NEW YORK, N. Y.

CATAMENIAL APRON.

Application filed May 27, 1922. Serial No. 564,162.

The present invention is a sanitary or catamenial apron to be worn by women over a rear portion of the person during certain periods, for the purpose of protecting the garments from menstruation, or may be ordinarily worn for the purpose of protecting light and delicate garments from being soiled by perspiration or the like.

All aprons made up to the present time 10 have been constructed of a flat piece of material devoid of fit or shape to parts of the anatomy over which they are worn. Aprons of this description never afford sufficient protection because of the fact that, when 15 the wearer is seated, the sides of the apron have a tendency to lie flat and allow the escape of fluid. Furthermore such aprons becoming readily disarranged causing discomfort and an embarrassing appearance of 20 the outer-garment.

The object of the invention is to provide a light, cool and odorless article of the above nature having an extremely neat appearance, assuring a high degree of sanitation, and remaining stable in its properly 25 adjusted position against embarrassing disarrangements, by fitting or conforming to the contour of the body in whatever position assumed without any creases or surplus of material causing wrinkles and consequent soiling of the outer-garments and 30 discomfort to the wearer, particularly when seated.

The invention broadly consists of a form 35 fitting apron, of the above stated character, having its protecting portion made of impervious material and having built thereinto the general configuration of those parts 40 of the body to which the apron is applied and covers.

One of the features of the invention resides in the apron being so constructed that its seat portion is concaved and extends rearwardly to conform to the buttocks of 45 the wearer, and that its side portions extend in a curved line around the sides of the hips and thigh of the wearer, resulting in the lower edge of the apron curving inwardly toward the knees and maintaining 50 this position without the aid of fasteners and the like.

Another feature resides in constructing the apron to have reinforcing stays or strips 55 extending lengthwise thereof which increase the durability of the apron and assures the

inward curving of its lower edge toward the knees of the wearer, when worn.

Sundry other objects and features of the invention will appear from the following 60 description.

In this specification and the annexed drawings, the invention is disclosed in the form in which it is considered to be the best, but the invention is not limited to such form because it is capable of being embodied in other forms; and it is to be understood that in and by the claims following the description herein it is intended to cover the invention in whatever form it may embody within the scope thereof.

In the drawings which illustrate the invention in the embodiment in which it is at present devised:

Figure 1 is a side view of a human form 75 showing the apron of the invention applied thereto,

Figure 2 is an enlarged prospective view of the apron viewing it from a general rearwardly direction,

Figure 3 is a transverse sectional view of 80 the apron taken on line 3—3 of Figure 2,

Figure 4 is a fragmentary transverse sectional view similar to Figure 3 showing the manner in which the the seams or reinforcing stays are formed, and

Figure 5 is a diagrammatic view illustrating the sections which compose the apron and showing the sections assembled in dotted lines.

Referring more particularly to the drawing in which like characters denote similar and like parts throughout the several views, one denotes an apron, of the above stated character, having a waist band 2. The apron comprises a fabric section *a* of suitable material such as net, nainsook, muslin, lawn or the like secured to the band 2 and a substantially rectangular sheet of impervious material *b*, such as rubber, secured to the lower edge of the fabric section. The outer edges of the section *a* and *b* are bound by suitable braid 3, in order to prevent undue tearing of the material. The waist band 2 takes the form of a suitable belt or tape to extend around the waist of the wearer and to be tied or otherwise fastened.

It is, of course, understood that the apron of this invention is intended to be supplementary to the usual napkins or bandages and the section *a* is of such dimensions as

will permit the impervious section *b* to extend from a point slightly below the hips to the knees of the wearer. The section *a* may be dispensed with without deducting 5 from the present invention and is merely provided for coolness and ventilation at and adjacent the waist.

The section *b* is constructed or formed to provide a concave and rearwardly extending 10 seat portion 4 in such a manner as to cause the lower edge portion *e* of the apron to skirt inwardly to lie close to the knees of the wearer as clearly shown in Figures 1 and 2. The upper edges of the side portions *d* of the impervious section *b* are cut on a substantial curve and thereby cooperate 15 with the formation of the concave seat 4 to cause the side portions *d* to extend forwardly around the hips and the sides of the 20 thighs of the wearer on a substantially curved line. In other words, the apron of this invention is so formed and shaped to conform to and lie closely against the buttocks, hips and thighs of the wearer so 25 that when in either seated or standing position the sides of the apron will not lie flat, but curve correspondingly with the form of the body, for the purposes above set forth. It will thus be seen that an apron so formed 30 or constructed will not become accidentally disarranged by the ordinary movements of the body which will cause bulky and unsightly appearances, as well as discomfort, but will remain in close fitting relation with 35 the body's contour. The apron 1 may be made of one piece by molding, stamping or pressing the material to such form, but in the present instance, the impervious portion *b* of the apron is shown as being made 40 up of a center section *c* and two side sections *d* of sheet rubber or other water resisting material arranged side by side and having their contiguous edges joined. As 45 clearly shown in Figure 5, the center section *c* has its side edges cut to diverge downwardly from its upper edge for a distance in the length of the section say, approximately at the point *x*. The inner side edges of the side section *d* are correspondingly 50 cut and thus when joined together, produce a concave seat portion *c* clearly shown in Figure 4. The sections *d* also have their upper edges cut downwardly on a slight curve or angularly as at *f*, before being 55 joined to the top section *a* so that the side portions *d* of the apron are drawn upwardly when connected to the lower edge of the top section *a*, whereby the sides of the apron 60 will extend around the sides of the wearer when the apron is worn. Also by reason of the pattern of these sections and the manner in which their edges are joined together 65 and to the fabric section *a*, the edge *e* will curve inwardly toward the knees of the wearer as indicated in the drawings.

The contiguous edges of the section *c* and *d* are joined together in the manner shown in Figures 3 and 4, by folding one of the edges upon itself and applying it on the edge of the adjacent section, as indicated at 70 *m* and *n*, and vulcanizing or otherwise suitably joining these edges together. By folding one of the edges upon itself, seams of considerable thickness and strength are 75 provided which act as reinforcing strips or stays in order to take up undue lengthwise strain on the section *b*, which strain may be occasioned when in seated positions; thus, increasing the durability and strength of 80 the garment. The curvature of the adjacent side edges of the sections *c* and *d* from their top edges to the point *x*, are in effect the same as darts should the sections *c* and *d* being of one piece.

Loops 5 and 6 are provided on the lower 85 side edges of the apron to be engaged by the garter or other fasteners in order to maintain the apron in position. These loops, however, are not necessary to the garment of this invention because of the distinct form fitting properties which it possesses but are merely provided for those who may wish to use them through abundance of precaution.

Having thus described the invention it will be observed that a very desirable apron has been provided which is truly form fitting and which overcomes numerous drawbacks and disadvantages enumerated in the 100 forepart of this specification.

What is claimed is:

1. A catamenial apron comprising a supporting section, an impervious apron section depending from the supporting section, a waist band on the supporting section, said impervious section having darts extending 105 from the top edge of the section, whereby a concave seat portion is formed in said section at the buttocks of the wearer.

2. A catamenial apron comprising a supporting section adapted to hang from the wearer's waist and a lower apron part comprising a central section and side sections, the contiguous upper side edges of said sections being curved and secured to each other 115 to form a concave seat portion in the body of said apron part at the buttocks of the wearer, the top portions of said sections being secured to the supporting section, the top edge of said central section being substantially straight and the top portions of 120 said side sections being cut diagonally with relation to the top of said central section before said sections are assembled to adapt the sides of said apron to the shape of the wearer.

3. A catamenial apron comprising a waist band, a supporting top section having a substantially straight lower edge, an impervious lower section having its upper edge 125

attached to the lower edge of the top section, the central portion of the top edge of the lower section being substantially straight and the side portions of said edge being so formed that when joined to the supporting section, the sides of the apron will be drawn about the sides of the wearer and the lower edge toward the knees.

5. A catamenial apron comprising a supporting section to hang from the wearer's waist, an impervious section secured to the supporting section, a waist band on the supporting section, said impervious section

10 of the section, whereby a concave seat portion is formed in said section at the buttocks of the wearer, the central portion of the top edge of the apron section between the darts being horizontal and the side portions of said top edge being cut diagonally with relation thereto before being joined to the supporting section.

In testimony whereof I have hereunto set my hand.

JACOB STEIN.
